ELEVATOR DOOR OPERATING SYSTEM

Charles E. Ellis, Jr., Mahwah, N. J., assignor to
Westinghouse Electric Elevator Company,
Chicago, Ill., a Corporation of Illinois

Application September 30, 1932
Serial No. 635,520

8 Claims. (Cl. 187—16)

My invention relates to elevator door operating systems and more particularly to door operating systems for plural elevators in which two or more cars are operated independently of each other in the same hatchway.

One object of my invention is to provide for electrically interlocking the hatchway doors of a plural-car elevator system in such manner that the opening of a hatchway door when a car stops 10 in front of it will prevent operation of that car until that door is reclosed but will not prevent operation of such other cars as may be disposed in the same hatchway.

Another object of my invention is to provide for 15 electrically interlocking the hatchway doors of a plural-car elevator in such manner that if one of the hatchway doors opens accidentally when no car is making a stop in front of it, none of the cars will be capable of operation until the door 20 is reclosed.

For an understanding of my invention, reference may be had to the accompanying drawings, in which

Figure 1 is a diagrammatic representation of a 25 plural-car elevator system embodying my invention, and

Fig. 2 is a diagrammatic representation of a plural-car elevator system embodying a modified form of my invention.

In Fig. 1 I have represented two elevator cars 30 1 and 2 disposed for operation in a single hatchway (not shown). Although plural elevators are essentially constructed for serving many floors in very tall buildings and may include more than 35 two cars, I have, for the sake of simplicity, illustrated only two cars as serving only four hatchway floors 3, 4, 5 and 6.

A hoisting drum D1 operated by a motor M1 is provided for operating the car 1 and a hoisting 40 drum D2 operated by a driving motor M2 is provided for operating the car 2.

The cars may be suspended from the hoisting drums D1 and D2 by a plurality of cables Ca and Ca' for independent operation in the hatchway in 45 any suitable manner such, for instance, as that disclosed in the copending application of Henry D. James, Serial No. 255,049, filed February 17, 1928, and assigned to the Westinghouse Electric & Manufacturing Company. A brake B1 is provided for controlling the operation of the hoisting drum D1 and a brake B2 is provided for controlling the operation of the hoisting drum D2.

The hatchway floors are provided with hatchway doors 7, 8, 9 and 10, each of which is disposed to slide sideways in opening or closing, and

each of which may be operated by any suitable door operating mechanism such as the hand operated toggle levers shown in the drawing.

The operating toggle levers for the door 9 comprise a pair of links 11 and 12 joined at their inner ends by a pivoted connection 13 and respectively connected at their outer ends by a pivot pin 14 to the door and by a pivot pin 15 to the wall of the hatchway (not shown). A handle 16 is provided for opening the levers. In opening the door, the handle 16 is moved to the right thereby breaking the toggle levers 11 and 12 from their straight line position and causing the door to slide towards the right to its open position. When it is desired to close the door, the handle 16 is moved downwardly to move the toggle levers to their straight line position and thereby move the door to its closed position. The toggle lever operators for the other doors are similar to that described for the door 9.

In order to prevent operation of the cars when a door is open, an interlock switch for each car is connected to the door operating mechanism at each hatchway opening. The interlock switches 17 and 18 for the door 9 are shown as operated by a shaft 19 which is pivotally connected to an extended portion 20 of the toggle lever 12. With this construction, when the door is opened, the end 20 of the lever 12 moves downwardly thereby pulling downwardly on the shaft 19 and moving the switches 17 and 18 to open position. Similar interlock switches are associated with each of the other doors and connected for operation by the door operating mechanism thereof.

In the upper portion of the drawing are shown two relays 23 and 24. The relay 23 is controlled by the interlocking switch 17 and also by the lower interlock switch at each door. When the relay 23 is energized, it closes a circuit to the motor M2 for operating car 2. When the switch 17 or the lower switch of any one of the doors is open, the relay 23 is deenergized thereby opening the control circuit to the motor M2 and preventing operation of the car 2 when any door is open.

The interlock relay 24 is controlled by the switch 18 and each of the upper interlock switches attached to the doors. When relay 24 is energized, it closes a circuit to the motor M1 in such manner as to permit operation of the car 1 but when one or more of the lower interlock switches at the doors are open, this relay is deenergized to open the circuit to the motor M2 to stop car 2.

In order to permit the operation of either car

110

while the other car is making a stop or standing at a floor, each of the interlock switches has associated with it a shunting switch. The shunting switches disposed to be closed by car 2 when that car is standing at a floor so as to permit the operation of car 1, are indicated as 26, 27, 28 and 29. The shunting switches disposed to be closed when car 1 is standing at a floor to permit the operation of car 2 during that period, are designated as 30, 31, 32 and 33.

Each of the shunting switches 30, 31, 32 and 33 to be operated by car 1 is mounted on an armature at the corresponding hatchway opening in position to be actuated to a closed position by a magnet IR mounted on the top of the car. The magnet IR is provided with a coil 34 which is connected to be energized through the deenergization of a relay 36. The winding of the magnet 36 is so interconnected with the elevator control system (not shown) that the magnet will be energized as the car reduces its speed and approaches a floor for a landing. This energizes the magnet coil to operate the particular armature-operated shunting switch at the door where the car is to stop and will, preferably, occur only when the car has stopped.

The shunting switches 26, 27, 28 and 29 to be operated by the car 2 are mounted upon armatures disposed at the hatchway doors in position to be operated by a magnet IR2 mounted on top of the car 2 in position to attract the armatures of the shunting switches when the car stops at the floors. The magnet IR2 is provided with an energizing coil 37 which is connected to and operated by a relay 38. The relay 38 is similar to the relay 36 and its coil is interconnected with the control system for the car 2 in such manner that the relay will be deenergized when the car makes a stop, thereby effecting energization of the magnet IR2 to close the shunting switch associated with the hatchway door at which car 2 stops.

The operation of the interlocking system is as follows: Let it be assumed that car 1 is standing at floor landing 6 with the hatchway door 10 open; that car 2 is standing at the floor landing 3 with the door 7 open, and that car 2 is to be moved upwardly to the floor landing 4. Car 2 cannot move until the door 7 at the landing is closed, for the reason that the interlock switch 40 and the shunting switch 30 at the floor landing 3 are open, thereby preventing energization of interlocking relay 23 and the consequent operation of the motor for car 2.

In preparing to move car 2 to floor 4, the handle 43 of the door operating mechanism for the door 7 is pressed downwardly to move the toggle levers 44 and 45 to their straight line position thus closing the door 7. The movement of the lever 45 causes its end portion 46 to move upwardly thereby closing the interlock switches 40 and 41.

The closing of the switch 40 completes a circuit for energizing the interlocking relay 23 to permit the starting of the car. This circuit extends from the supply conductor L1 through conductor 47, the coil of relay 23, conductor 48, one side of switch 49, conductor 50, the contact members of shunt switch 33, conductor 51, the other side of switch 49, conductor 52, the contact members of switch 17, conductor 53, the contact members of switch 54, conductor 55, the contact members of switch 40 (now closed by the closing of the door 7) and conductor 56 to supply conductor L2. The energization of relay 23 closes its contact members thereby completing a circuit permitting

the operation of the motor M2 to move the car 2 upwardly. This circuit extends from supply conductor L1 through conductor 57, the motor M2, conductor 58, the coil of the brake B2, conductor 59, the contact members of relay 23 and conductor 60 to a control circuit represented by 61.

Upon operation of the control circuit (not shown) for car 2 to move the car upwardly and stop it at the second floor, the relay 38 is energized through a circuit extending from the supply conductor L1 through conductor 62 and the coil of relay 38 to the control system designated as 63. The energization of the relay 38 opens its contact members and thereby opens the circuit for the coil of the magnet IR2 on the car 2. The deenergization of magnet IR2 releases the armature of the shunting switch 26 at the floor landing 3 thereby restoring the interlock switch 40 to effective condition.

As the car moves to its stop at floor landing 4, its control circuit is operated to decelerate the car and bring it to a stop, consequently, the relay 38 is deenergized and its contact members close to complete a circuit for energizing the magnet IR2 on the car 2 to attract the armature of shunting switch 27 and close that switch at floor 4. This circuit extends from supply conductor L1 through conductor 64, the coil 37 of magnet IR2, conductor 65, the contact members of relay 38 and conductor 66 to supply conductor L2. The attraction of the shunting switch 27 by the magnet IR2 causes the contact members of that shunting switch to provide a shunt circuit around the interlocking switch 54 at floor 4.

After the car 2 stops at the floor landing 4, the handle 67 of the door operating mechanism of that floor is moved downwardly thereby breaking the toggle levers 68 and 69 from their straight line position to effect the opening of the door 8. As the central portion of the lever 69 moves upwardly, its right-hand end portion 70 moves downwardly thereby opening the interlock switches 54 and 71 to prevent operation of the cars while door 8 remains open. However, as previously described, the shunt switch 27 has been closed by the operation of the magnet IR2 and thereby provides a shunt circuit around the interlock switch 71 to permit the car 1 to operate when the door at the floor landing at which car 1 is standing is closed.

Assuming now that car 1 is to be moved from floor landing 6 to floor landing 5, consequently the door 10 is closed, thereby closing the interlock switches 49 and 72 in a manner similar to the closing of the interlock switches associated with the door 18. The closing of the interlock switch 72 permits operation of the car 1 by energizing the interlocking relay 24 by a circuit extending from supply conductor L1 through conductor 73, the coil of relay 24, conductor 74, the contact members of switch 72, conductor 75, the contact members of switch 18, conductor 76, the contact members of the right-hand side of interlock switch 71, conductor 77, the contact members of shunt switch 27, conductor 78, the left-hand side of switch 71, conductor 79, the contact members of switch 41 and conductor 80 to supply conductor L2.

The energization of the relay 24 closes its contact members and thereby completes a circuit from the supply conductors to the control system of the car 1 whereby the brake B1 and the motor M1 may be energized to release the car and move it downwardly. This circuit extends from supply conductor L1 through conductors 145 150

57 and 81, the motor M1, conductor 82, the coil of brake B1, conductor 83, the contact members of relay 24, and conductor 84 to the control circuit designated as 85. The energization of the 5 brake B1 releases the brake and permits movement of the car. The energization of the motor M1 moves the car until it is stopped by operation of the control system (not shown).

Inasmuch as the relay 36 is interconnected 10 with the control system for car 1, the relay is energized when the car is being operated from one floor to another by a circuit extending from supply conductor L1 through conductor 86, the coil of relay 36 and conductor 87 to the control 15 system designated as 88. The energization of relay 36 opens its contact members and thereby deenergizes the magnet IR on car 1 to prevent it from effecting operation of any shunt switch until car 1 is stopped at a landing.

20 Assuming now that car 1 is brought to a stop at floor landing 5 then the relay 36 is deenergized by reason of its interconnection with the car control circuit and closes its contact members to energize magnet IR on car 1 by a circuit extending from supply conductor L1 through conductor 90, contact members of relay 36, conductor 91, the coil 34 of magnet IR and conductor 92 to the supply conductor L2.

25 The energization of the magnet IR as the car stops at the floor landing 5, closes the contact members of shunt switch 32 thereby completing a shunt circuit around interlock switch 17.

30 After car 1 stops, the door 9 is opened, thereby opening the interlocking switches 17 and 18 to prevent operation of the cars while door 9 is open. However, inasmuch as the shunt switch 32 is closed, the car 2 may be operated independently of car 1 (provided the door at the floor landing where the car 2 is standing is closed) 40 by reason of the fact that the interlocking relay 23 is energized to permit the circuit to the motor M2 and the brake B2 to be completed. The energizing circuit for the interlock relay 23 extends from supply conductor L1 through conductor 45 47, the coil of relay 23, conductor 48, the contact members of switch 49, conductor 52, one side of switch 17, conductor 93, the contact members of shunt switch 32, conductor 94, the other side of switch 17, conductor 53, the contact members of switch 54, conductor 55, the contact members of switch 40 and conductor switch 56 to supply conductor L2. The energization of relay 23 closes its contact members and thereby permits car 2 to be moved downwardly from the floor landing 55 4 whenever desired.

Referring now to Fig. 2, in the modified form of my invention illustrated therein, the shunt circuits around the interlock switches at the doors are controlled by contact segments and brushes 60 on the floor selectors of the cars instead of by the magnets IR and IR2 on the cars. As shown on Fig. 2, the hoisting drum D1 of car 1 is provided with a winding spool 100 to which is secured one end of a cable 101, the other end of which passes over a pair of pulleys 102 and 103 to a brush 104 disposed between two vertical rows of contact segments 105 on the floor selector FS1 for car 1. When the car moves upwardly and downwardly, the brush 104 moves upwardly and downwardly between the rows of contact segments and connects them in accordance with the position of the car at the floors so that with car 1 at any floor, the shunt circuit corresponding to that floor for car 2, is completed.

70 75 In a similar manner, the hoisting drum D2

for car 2 is connected by a cable 108 with a brush 109 disposed between two rows of contact segments 110 on the floor selector FS2 for car 2. The brush 109 is moved upwardly and downwardly between the rows of contact segments 110 in 80 accordance with the movement of the car, thereby completing the shunt circuit for car 2 at the floor corresponding to the position of car 1.

An assumed operation for the system shown in Fig. 2 is as follows:

Assuming that car 1 is at the uppermost floor, with door 10 open; that the door 7 at the lowermost floor is closed and that car 2 is ready to start upwardly, then the brush 104 of car 1 will connect the contact segments 112 and 113 on the floor selector FS1 thereby completing a circuit for energizing the interlock relay 23 to prepare a circuit for the operation of car 2. The circuit for relay 23 extends from supply conductor L3 through conductor 115, the coil of relay 23, conductors 116 and 117, contact segment 112, brush 104, contact segment 113, conductors 118 and 119, the contact members of interlock switch 18, conductor 120, the contact members of interlock switch 71, conductor 121, the contact members of 90 interlock switch 41, and conductor 122 to supply conductor L4. The energization of the relay 23 closes its contact members and connects the conductors 59 and 60 to complete the circuit for operating the hoisting motor D2 of car 2, as shown 100 105 in Fig. 1.

Assuming now that car 2 stops at the second floor, the door 8 thereat is opened, the door 10 at the top floor is closed and car 1 prepares to descend, then the opening of the contact members 110 on interlock switch 54 for door 8 opens the circuit for the interlock relay 24 of car 1. However, the relay is not deenergized, the brush 109 has moved upwardly to the contact segments 122 and 123 under the operation of car 2 and has closed the shunt circuit for energizing the relay 24 to permit the operation of car 1. The circuit for relay 24 thus completed extends from supply conductor L3 through conductor 124, the coil of relay 24, conductor 125, the contact members of interlock switch 49, conductors 126 and 127, the contact members of interlock switch 17, conductors 128 and 129, the contact segment 122, brush 109, contact segment 123, conductor 130, the contact segments of interlock switch 40 and 125 conductor 131 to supply conductor L4, thereby maintaining the interlock relay 24 in its energized condition wherein its contact members connect the conductors 83 and 84 for operating the hoisting drum D1, as shown in Fig. 1.

Obviously, if a door is opened while the cars are running, the interlock switches at that door will be opened and the interlocking relays 23 and 24 will be deenergized, as shown in both Fig. 1 and Fig. 2, thereby opening the motor control 130 135 circuits and stopping the cars.

By the assumed operation of the cars and the interlock switches in either Fig. 1 or Fig. 2, it is seen that I have provided a door operating system which will prevent any unsafe operation 140 of the cars in a plural elevator while any one of the doors is open but which will not prevent the independent operation of the cars under safe conditions.

Although I have illustrated and described only 145 two specific embodiments of my invention, I desire it to be understood that the system may be changed and modified in many ways without departing from the scope of the invention.

I claim as my invention:

1. In an elevator system having a plurality of 150

- cars operable past a plurality of doors in a hatchway, means associated with each door and responsive to an open position thereof for preventing operation of any car, and means operably responsive to the stopping of a car at a door for rendering ineffective the preventing means associated with that door for the other cars. 5
2. In an elevator system having a plurality of cars operable past a plurality of doors in a hatchway, means associated with each door and responsive to an open position thereof for preventing operation of any car, and means operably responsive to the presence of a car at a door for rendering ineffective the preventing means associated with that door for the other cars. 10
3. In an elevator system having a plurality of cars operable past a plurality of doors in a hatchway, individual means for moving said cars, means associated with each door and responsive to an open position thereof for preventing operation of the moving means for any car when a door is open, and means operably responsive to the stopping of a car at a door for rendering ineffective the preventing means associated with that door for the other cars. 15
4. In an elevator system having a pair of cars operable past a plurality of doors in a hatchway, individual electric motors for moving the cars, circuits for operating said motors, means associated with each door and operably responsive to an open position thereof for disabling said motor operating circuits when a door is open, and means operably responsive to the stopping of a car at a door for rendering ineffective the circuit opening means for the other car. 20
5. In an elevator system having a pair of cars operable past a plurality of doors in a hatchway, individual motors for moving the cars, a circuit for each motor, an electromagnetic switch associated with each motor and disposed when deenergized to disable the circuit for that motor, a circuit for each electromagnetic switch, means associated with each door and responsive to an open position thereof for opening the electromagnetic switch circuits and thereby disabling the motor circuits when a door is open, and means operably responsive to the stopping of a car at a door for completing a shunt circuit for energizing the electromagnetic switch to restore the motor circuit for the other car to permit said other car to operate while said first car is stopping at the door. 25
6. In an elevator system having a pair of cars operable past a plurality of doors in a hatchway, individual motors for moving the cars, a circuit for each motor, an electromagnetic switch associated with each motor for controlling the operation of that motor, a circuit for each of said electromagnetic switches, means associated with each door and responsive to an open position thereof for controlling the circuits of the electromagnetic switches to disable the car motor circuits while a door is open, and means operably responsive to the stopping of a car at a door for rendering the electromagnetic switch ineffective to disable the motor circuit for the other car while said first car is making said stop. 30
7. In an elevator system having a pair of cars operable past a plurality of doors in a hatchway, means associated with each door and responsive to an open position thereof for preventing operation of either car when a door is open, an electromagnetic means disposed on each car, and means operably responsive to the stopping of a car at a door for energizing the electromagnetic means on that car to render ineffective the preventing means associated with that door for the other car. 35
8. In an elevator system having a pair of cars operable past a plurality of doors in a hatchway, individual electric motors for moving said cars, a control circuit for each of said motors, a pair of interlock switches connected to each door and responsive to an open position thereof for opening the control circuits when the door is open to prevent operation of the cars, normally open shunt control circuits around such interlock switches, a plurality of magnetizable switches disposed at each door for said shunt control circuits, an electromagnetic means disposed on each car in position to approach closely to a corresponding magnetizable switch when the car is at the door, and means operably responsive to stopping a car at a door for energizing the electromagnetic means on that car to close its corresponding magnetizable switch for completing the shunt control circuit for the other car and thereby permit operation of that other car while said first car is at said door. 40
